UNITED STATES PATENT OFFICE.

ADAM HINKEL AND JACOB HINKEL, OF OFFENBACH-ON-THE-MAIN, GERMANY, ASSIGNORS TO THE FIRM OF E. PH. HINKEL, OF OFFENBACH-ON-THE-MAIN, GERMANY.

FASTENER FOR SATCHELS, PURSES, &c.

SPECIFICATION forming part of Letters Patent No. 700,329, dated May 20, 1902.

Application filed February 25, 1902. Serial No. 95,523. (No model.)

To all whom it may concern:

Be it known that we, ADAM HINKEL and JACOB HINKEL, subjects of the German Emperor, and residents of Offenbach-on-the-Main, 5 Germany, (whose postal address is 56 Geleitsstrasse, Offenbach-on-the-Main, Germany,) have invented certain new and useful Improvements in Fasteners for Satchels, Purses, and the Like, of which the following is a specification.

The present invention relates to a fastening device for satchels, purses, and the like. The said device has the advantage over those hitherto known of being more easy to manipulate.

In the annexed drawings, Figure 1 is a cross-section, and Fig. 2 a perspective view, of the device. Fig. 3 is a cross-section illustrating a slight modification.

The fastening device comprises two plates or wings *a* and *b*, which when the satchel is closed stand apart and away from the frame or mouth in the manner of two folded butterfly-wings. One plate *a* is soldered or otherwise attached securely to one part *c* of the frame, and the other plate *b* is similarly attached to the movable part of a hinge *d*. The other part of the hinge is secured to the fixed plate *a*. The two cheeks of the hinge have the form of sections of tubes, and when the fastening device is at rest they abut against each other with their lower parts, so that when the frame is open the plate *b* cannot fold downward and prevent the closing of the frame. The arm *e*, bent outward substantially at a right angle from the plate *b*, is provided at its center with an aperture into which the fastening-pin *g* on the other part *f* of the frame engages when the frame is closed.

Fig. 3 shows a modification in the shape of the frame.

Simple compression of the two plates causes the frame to be opened.

The fastening device is more particularly suited for ladies' purses or suspended satchels, which can be easily opened and closed with two fingers of one hand.

What we claim is—

1. In a fastener for satchels, purses and the like, the combination with a frame consisting of two halves, of two plates or wings one of which is secured to one half of the frame, and the other plate being hinged, and means in connection with the other half of the frame for locking said second plate, substantially as described.

2. In a fastener for satchels, purses and the like, the combination with a frame consisting of two halves, of two plates or wings, one of which is secured to one half of the frame, a hinge between said plates to which the other plate is secured, said latter plate having an aperture adapted to be engaged by a catch or pin on the second half of the frame, substantially as described.

3. In a fastener for satchels, purses and the like, the combination with a frame consisting of two halves, of two plates or wings, one of which is secured to one half of the frame, a hinge between said plates consisting of two parts to one of which the other plate is secured, the other part of said hinge being secured to the first-mentioned plate, an arm substantially at right angles to said second plate and provided with an aperture; and a pin or catch on the second half of the frame, adapted to enter said aperture, substantially as described.

4. In a fastener for satchels, purses and the like, the combination with a frame consisting of two halves, of two plates or wings, one of which is secured to one half of the frame, a hinge between said plates consisting of two parts, of segmental section, to one of which parts the other plate is secured, the other part of said hinge being secured to the first-mentioned plate, an arm secured substantially at right angles to said second plate and provided with an aperture, and a pin or catch on the second half of the frame, adapted to enter said aperture substantially as described.

5. In a fastener for satchels, purses and the like, the combination with a frame consisting of two halves, of two plates or wings *a* *b*, one

of which *a* is secured to one half *c* of the frame, a hinge *d* between said plates consisting of two parts of tubular section the lower ends of which abut against each other when the frame is closed, and to one of which parts the other plate *b* is secured, the second part of said hinge being secured to the first-mentioned plate *a*, an arm *e* substantially at right angles to said second plate *b* and provided

10 with an aperture, and a pin or catch *g* on the

second half *f* of the frame, adapted to enter said aperture substantially as described.

In testimony whereof we have signed our names to this specification in the presence of two subscribing witnesses.

ADAM HINKEL.
JACOB HINKEL.
